UNITED STATES PATENT OFFICE.

ANDREW L. RIKER, OF SHORT HILLS, NEW JERSEY, ASSIGNOR TO THE "LOCOMOBILE" COMPANY OF AMERICA, OF NEW YORK, N. Y., A CORPORATION OF WEST VIRGINIA.

SPARK-ADJUSTING STARTING MEANS FOR AUTOMOBILES.

No. 906,290.

Specification of Letters Patent.

Patented Dec. 8, 1908.

Application filed November 4, 1902. Serial No. 130,032.

To all whom it may concern:

Be it known that I, ANDREW L. RIKER, a citizen of the United States, residing at Short Hills, in the county of Essex and State of New Jersey, have invented an Improvement in Spark-Adjusting Starting Means for Automobiles, of which the following description, in connection with the accompanying drawings, is a specification, like letters on the drawings representing like parts.

My invention relates to motor vehicles of the type employing internal combustion engines, wherein the ignition is produced by an electric spark.

15 In starting an internal combustion engine, the sparking and ignition should occur immediately at the beginning of the working stroke of the piston, but as the engine gathers speed, the sparking must be advanced, 20 it occurring, at high speed, frequently at or about the middle of the return stroke next preceding the working stroke, this early ignition being necessary not only to furnish a cushion for the reciprocating parts of the 25 engine, but also to provide the expansive power resulting from the ignition in sufficient time to perform its work in driving the rapidly moving piston.

The prevailing practice at present is to 30 provide motor vehicles with suitable speed responsive, governing means, which shall advance the sparking in proportion to the increase of speed, but I have found it difficult to provide a speed responsive device or 35 governor which shall be reliable and properly responsive at high speeds and which will also produce the required adjustments of contacts at very low speeds, particularly when the engine is stopped and the contacts 40 are to be left in position for again starting the engine.

My present invention comprehends a speed responsive or governing means which shall furnish the required adjustment of contacts 45 for high speeds in combination with independent adjusting means preferably manually operable for preliminarily adjusting the contacts for sparking in such a manner as to enable the engine to be started.

50 My invention will best be understood from

a description of one embodiment thereof in a typical motor vehicle.

Referring to the drawings,—Figure 1, in side elevation, illustrates a typical motor vehicle equipped with devices illustrating one embodiment of my invention; Fig. 2 is an enlarged detail of one form of speed responsive or governing means; Fig. 3 is a longitudinal section on the dotted line, 3—3, Fig. 2; Fig. 4 is a detail illustrating the fixed and movable contacts and independent means for adjusting the same for starting the engine; and, Fig. 5, a diagram illustrating the connections between the governor and throttling devices.

Referring to the drawings, particularly to Fig. 1, the motor vehicle may be of any suitable or desired type, the same as illustrated comprising the steering and propelling wheels, *a*, *b*, the spring supported frame, *c*, body, *c'*, internal combustion engine, *E*, clutch, *e*, transmission gear, *F*, jackshaft, *f*, suitably connected with and to rotate the propelling or driving wheels, *b*, all of which are and may be of usual or desired construction, so far as concerns my present invention.

Referring now particularly to Figs. 2, 3, and 4, the engine crankshaft as here shown, is provided with a pinion, *p*, which drives a wheel, *p'*, keyed to and rotating the shaft, *e^{ss}*, which may be the cam shaft for actuating the valve mechanism of the engine. This wheel, *p'*, carries a pair of centrifugal weights, *p¹*, mounted in usual manner, as, for instance, upon the arms, *p⁵*, fulcrumed at *p⁶*, upon the wheel and having their outer ends controlled by springs, *p⁷*, tending to draw said weights and arms normally towards the axis of rotation of the wheel.

The free, spring controlled ends of the weighted arms, *p⁵*, are connected by links, *p⁸*, with the radial arms, *p⁹*, of a sleeve, *p¹⁰*, loosely mounted upon the cam shaft, *e^{ss}*. This sleeve at its outer end, at the left, Fig. 3, carries an insulating head, *p¹¹*, in which, see Fig. 4, is set a contact piece, *p¹²*, the face of which is flush with the peripheral face of the said head. Thus, the sleeve, *p¹⁰*, carrying this contact member, *p¹²*, not only rotates by and with the cam shaft wheel, *p'*, but it 100

has a further movement relative to the said wheel produced by the varying positions of the centrifugal governor weights, p^4 , due to the speed of rotation of said wheel, which 5 causes the said contact member, p^{12} , to occupy a more or less advanced position or lead relative to its wheel, according to the rotative speed of the latter.

Back of the insulating head, p^{11} , and preferably rotatably carried by the inclosing case, p^3 , referred to, is a plate, p^{13} upon which are mounted and insulated therefrom four contact posts, p^{14} , (one for each cylinder of the engine, a four cylinder engine 15 being herein assumed) shown as spaced uniformly 90 degrees one from the other and carrying respectively the four contact brushes, p^{15} , resting at their ends upon the periphery of the insulating head, p^{11} , referred to, and adapted on rotation of the said head to successively make contact with the rotating contact member, p^{12} , on the said head. Thus, at each complete rotation of the cam shaft wheel, and the head, p^{11} , there 25 occur four successive closures of the electric circuits, said closures being for the four cylinders of the engine, to ignite the contents thereof at the proper times for operating the engine in the manner hereinbefore described.

30 As the speed of the engine increases, it is necessary to advance the sparking for the several cylinders, since increased speed of rotation requires earlier ignition. This is accomplished with the construction shown, 35 for as the speed increases, the governor weights assume positions further from their axes of rotation, thus turning the sleeve, p^{10} , to advance the position of the contact member, p^{12} , to cause it to make earlier contact 40 with the several brushes within which it rotates.

I control the supply of mixture for the engine also from this governor: Referring to Fig. 3, the pivot pins in the outer ends of 45 the radial arms, p^9 , and to which the links, p^8 , are jointed, which pins are here designated p^{16x} , are shown as extended through the wheel, p' , the arms of which are suitably shaped, to provide sufficient openings there- 50 for, said pins at their remote ends passing through and closely fitting suitable openings in a circumferentially grooved disk, p^{16} , loosely mounted upon the hub of the cam shaft driving wheel, p' , so that rocking 55 movement of the radial arms, p^9 , due to the action of the governor weights, will cause a corresponding rocking or rotative movement of the said disk, p^{16} , also on and relative to the said shaft, e^{24} .

60 The hub of the disk, p^{16} , is grooved spirally at p^{17} , to receive a pin, p^{18} , projecting radially from the hub of the wheel, p' , so that as the said grooved disk is rocked or rotated back and forth under the action of the governor 65 weights, the spiral groove in the hub thereof

acting upon the radial pin, p^{18} , will cause the said grooved disk to move axially in one or the other direction, according to the direction of its rotation, and consequently, corresponding to the movements of the governor weights. The groove in the periphery of this disk, see Fig. 5, receives the end of a lever, p^{19} , fulcrumed at p^{20} , in the casting, p^3 , and bearing at its free end upon a spring, p^{21} , seated against a collar, p^{22} , fast on a rod, 70 p^{23} . This rod is jointed at p^{24} , to an arm, p^{25} , which is fast upon the upper end of a spindle or stem, n^6 , of any suitable throttle, which controls the supply of combustible mixture to the engine; consequently, as the 75 said grooved wheel is shifted axially by the shifting governor weights, it will through the lever, spring and rod referred to, impart a corresponding rocking movement to the throttle, to increase or reduce the supply 80 of mixture to the engine cylinders, and the spring, p^{26} , engaging the said arm, p^{25} , returns the latter upon return movement of the governor weights. Thus, the governor 85 weights not only adjust the times of ignition, as required to maintain the speed at the proper point, but regulate also the supply of mixture to the engine cylinders for the same purpose. The centrifugal governor may therefore be relied upon to maintain a 90 substantially constant speed, which speed may be varied as desired by proper adjustment of the weights and their connections. In operating the vehicle, however, it becomes necessary frequently to reduce the 95 speed of the vehicle below that normally maintained by the automatic governor, and it is equally desirable, when occasion requires, to be able to increase the speed beyond that normally maintained by the 100 governor. To provide for this I have connected 105 with the cylindrical throttle arm, p^{25} , a rod, p^{27} , shown as leading to and connected with an arm, p^{28} , at the bottom of a rod, p^{29} , mounted in bearings preferably upon and at the side of the steering post, p^{30} , said rod, p^{29} , being fitted at its upper end with a handle, p^{31} , conveniently arranged with reference to the steering handle, p^{32} . Thus the 110 operator, with one or the other of his hands, while steering the vehicle, may move the said handle, p^{31} , in one direction, as to the left, Fig. 5, and thus rotate the cylindrical throttle farther than it is rotated by the 115 automatic governor and reduce the supply of mixture for the engine beyond that determined by the automatic governor and reduce the speed below the normal governor 120 speed to any desired extent. On the other hand, by swinging said handle in an opposite direction, the throttle may be turned, to increase the supply of mixture to the engine to increase its speed, notwithstanding the 125 automatic governor is tending to hold it down, the spring, p^{21} , between the rod p^{28} , 130

135

and the arm, p^{19} , permitting the said rod to be moved in opposition to the said arm without disturbing the position of the latter as fixed by the governor. In any event, whether 5 the speed be thus increased or reduced relative to the normal governor speed of the engine, the governor responds to the change in speed, and immediately adjusts the lead of the contact member, p^{12} , to meet the new 10 speed. As heretofore stated, however, a governor or speed responsive device which is sensitive and accurate when running at high speeds, is not usually sensitive or accurate at very low speeds approaching a state of rest; 15 and I have found that while the governor shown is capable of responding quickly to changes in running speed and keeping the lead of the sparking contact p^{12} always at a proper point for the particular speed for 20 the time being, yet when the machine is stopped and the parts assume a state of rest, said governor does not with certainty restore the said contact, p^{12} , to the required position to cause ignition at the very beginning 25 of the working strokes of the several cylinders. As a rule, a governor of this type when stopped will leave the said contact p^{12} in position where, if the engine be started, it would cause premature ignition, 30 i. e., ignition near the close of the return stroke next preceding a working stroke; which, of course, would prove detrimental. To overcome this objection, referring to Fig. 4, I have attached to or upon the brush 35 carrying plate, p^{13} , a flexible connection or wire, 50, which is carried to and about a suitable pulley or sheave, 51, thence upward to and connected with a handle lever, 52, fulcrumed at 53, upon a suitable support, 40 preferably on the dash board. The said lever may be provided as herein shown with a suitable latch device, 54, coöperating with a toothed sector, 55, by which said lever is held in desired position. 45 A spring, 56, attached to a suitable support is connected with the plate, p^{13} , said spring tending to rotate the said plate normally in a direction indicated by the arrow, Fig. 4, to advance the brushes, p^{16} , and thereby 50 by the time of sparking; such rotation of the said plate and brushes being resisted by the wire and lever, 52.

Assuming the engine to have stopped with its movable contact, p^{12} , in the position 55 shown in Fig. 4, and with the brushes in the full line positions in the said figure, such position of said contact, p^{12} , relative to the cranks and pistons of the engines being such as would furnish the proper sparking 60 for the engine when running at normal or slightly reduced speed, obviously would be too early for the initial starting of the engine. It is impossible to give to the said contact, p^{12} , a retrograde movement because of its connections with the

governor weights, which are in a state of rest; consequently the lever, 52, is dropped into its dotted position, Fig. 4, thereby permitting the spring, 56, to rotate the plate, p^{13} , in the direction of the arrow to advance the 70 brushes relative to the rotatable contact, p^{12} , which is equivalent to giving a retrograde movement to the said contact to delay the ignition for the several cylinders. The parts are so adjusted that when the said handle 75 lever, 52, is dropped into its lowermost position, the adjustment of the brushes will be correct for starting the engine, that is, for producing the ignition at the commencement 80 of the working stroke of each piston. The engine having been started, after it has acquired such speed that the governor commences to respond, the handle lever, 52, is again raised into elevated position, thus restoring the brush carrying plate, p^{13} , to its 85 normal position against the tension of the spring, 56, and leaving the control of the sparking of the engine thereafter wholly in the governor, which exercises its control by varying the lead of the rotating contact, p^{12} . 90 By this arrangement, I am enabled to construct the governor and its connections with the movable contact in a manner that will produce the best results and most accurate and sensitive adjustment of the contacts for 95 running speeds of the engine, thus enabling me to derive the greatest benefit from the throttling of the mixture herein described. At the same time, the hand adjustment of the ignition contacts provides for the starting 100 of the engine, without danger of its reversing to the injury of the one attempting to start it.

My invention obviously is not limited to the particular embodiment thereof here 105 shown and described, as the same may be varied within the spirit and scope of the invention.

Claim.

1. In a motor vehicle provided with an internal combustion engine having sparking means, the combination with said engine and ignition contacts therefor, of speed responsive means to govern the relative operation of said contacts, and simultaneously operable means independent of the speed responsive means to govern the relative operation of said contacts for starting, while maintaining a like cycle of engine operation.

2. In a motor vehicle the combination of 120 an internal combustion engine provided with sparking means, means for throttling the combustible mixture therefor, ignition contact devices, a speed governor and connections for adjusting the ignition to follow the 125 throttled speed of the engine, and simultaneously operable means separate from said governor and its connections, to adjust the ignition for starting the engine.

3. In a motor vehicle provided with an in- 130

- ternal combustion engine, the combination with throttling means therefor of a throttle controller responsive to the speed variations of the engine, means to throttle the engine 5 independently of the speed thereof, sparking means having a timing adjustment responsive also to the same speed variations of the engine, and means under the control of the operator also to vary the timing of said 10 10 sparking means for starting the engines irrespective of the engine speed.
4. In a motor vehicle provided with an internal combustion engine employing sparking means, the combination with said engine of independently and simultaneously 15 operable governor and manually controlled sparking means therefor to effect independent adjustments of the time of ignition relatively to the working stroke while maintaining 20 the same cycle of engine operation.
5. In a motor vehicle provided with an internal combustion engine employing sparking means, the combination with said engine, of circuit closing and breaking means 25 including a rotary contact and one or more coöperating contact brushes, of governor means comprising a governor and its connections with said circuit closing and breaking means to change the relative angular 30 position of said contact and said brushes, and means independent of said governor means to vary the position of said contact brush or brushes for starting the engine.
6. In a motor vehicle provided with an internal combustion engine, a throttling device therefor, controlling means for said throttling device responsive to variations in the engine speed, means for controlling said 35 throttling device irrespective of the speed responsive means, sparking means having a timing adjustment responsive also to the same speed variations of the engine, and means also to adjust the timing of said 40 sparking means during engine operation independently of said speed controlled means and said throttle controlling means.
7. In a motor vehicle provided with an internal combustion engine, a throttling device therefor, means responsive to variations 50 in the engine speed for controlling said throttling device, manual operating means for controlling said throttle, sparking means for said engine having a timing adjustment responsive also to the same speed variations 55 of the engine, and manually operative means for adjusting the timing of said sparking means during engine operation independently of said manually operated throttle controlling means.
- 60 8. An internal combustion engine having throttling means therefor, a controlling device for said throttling means responsive to the speed variations of the engine, means also to control said throttling means irrespective 65 of the speed responsive means,
- sparkling devices having a timing adjustment to cause changes in the ignition to respond to speed changes in the engine, and additional controlling means also to adjust the timing of said sparkling means during 70 engine operation.
9. In a motor vehicle provided with an internal combustion engine, the combination with said engine of ignition means therefor, means responsive to the engine speed to vary 75 the timing of ignition relatively to the working stroke, and separate controlling means also to vary the time of ignition relatively to the working stroke on the same cycle of operation independently of the engine speed. 80
10. In a motor vehicle provided with an internal combustion engine employing sparking means, the combination with said engine of ignition contacts therefor, means responsive to engine speed to adjust the sparking 85 in advance of the working stroke for relatively high speeds, and separate controlling means to adjust said contacts independently of said speed responsive means to provide retarded ignition at or about the beginning 90 of the working stroke for starting or on relatively slow speeds.
11. In a motor vehicle an internal combustion engine, ignition contacts for said engine, a speed governor controlling said 95 contacts to adjust the timing of the engine ignition to correspond with the engine speed, an engine throttle also controlled by said governor, a controlling lever within the control of the vehicle operator, and connecting 100 means between said lever and said ignition contacts permitting the manual adjustment of said contacts independently of the engine speed or the throttle control.
12. In a device of the class described, the combination with an internal combustion engine provided with fuel throttling means and ignition contacts, of speed governor means for controlling said contacts and said 105 throttling means, and means independent 110 thereof for separately governing the relative operation of said contacts for starting and independent of the action of said governor thereon.
13. In a device of the class described, an internal combustion engine provided with 115 sparking means, fuel throttling means for said engine, means including a speed responsive governor for adjusting the ignition to follow the speed of said engine, simultaneously operable means to adjust the ignition for starting the engine independently 120 of said governor adjustment, and means for limiting the action of said governor on said throttling means. 125
14. A motor vehicle provided with an internal combustion engine having a fuel throttling device and sparking means, the combination therewith of an independently and simultaneously operable governor and 130

manually controlled sparking means therefore, manually controlled contact devices for said sparking means to effect independent adjustments of said throttling device and 5 time of ignition relative to the engine speed while maintaining the same cycle of engine operation, and means for limiting the action of said governor on one of them.

In testimony whereof, I have signed my name to this specification, in the presence 10 of two subscribing witnesses.
